United States Patent Office.

JOHN H. KEYSER, OF NEW YORK, N. Y.

Design No. 4,817, dated April 18, 1871.

DESIGN FOR AN OVEN.

The Schedule referred to in these Letters Patent and making part of the same.

I, JOHN H. KEYSER, of the city and county of New York, in the State of New York, have invented and produced a new and original Design for the Oven of a Stove, of which the following is a specification, reference being had to the accompanying photographic drawing making part of the same.

The photograph represents the new design for an oven mounted upon a stove, and shows the front and one end of the oven.

The nature of my design consists of a dog and a cat at bay, separated by a vertical bar, which is connected at the top with two columns by means of arches.

The columns and the arches above referred to may be ornamented in any suitable manner, and the words "busy bee" may be represented above the belligerent animals.

I claim as my invention—

The design herein represented for the front of an oven.

JOHN H. KEYSER.
